LOOSE-LEAF BINDER

Paul O. Unger, Elmhurst, and Fred D. Wedge, Lombard, Ill., assignors to Wilson-Jones Company, Chicago, Ill., a corporation of Massachusetts

Application April 2, 1934, Serial No. 718,646

21 Claims.

(Cl. 129—8)

This invention relates to a loose-leaf binder which may be expanded to vary its capacity.

It is an object of this invention to provide a loose-leaf binder of variable capacity capable of holding a plurality of sheets under compression. It is a further object of this invention to provide means for adjusting the back of the binder to the contents with greater accuracy than has heretofore been possible. Other objects of this invention will become apparent upon reading the following description taken in conjunction with the accompanying drawings, in which:

Figure 1 is a top plan view of the back of a loose-leaf binder embodying the invention, with parts broken away to facilitate illustration of the structure;

Figure 2 is a rear plan view of the binder back with the outer rounded back plate removed;

Figure 3 is a cross sectional view of the binder; Figure 4 is an enlarged fragmentary view of the ratchet and pawl mechanism for controlling the expansion of the binder;

Figure 5 is a longitudinal sectional view taken generally along the line V—V of Figure 2;

Figure 6 is an end elevation of the binder;

Figure 7 is a longitudinal sectional view taken generally along the line VII—VII of Figure 3;

Figure 8 is a rear plan view of a modified embodiment of the invention, with parts broken away to facilitate illustration of the structure;

Figure 9 is a cross sectional view taken generally along the line IX—IX of Figure 8;

Figure 10 is a fragmentary perspective view of the binder associated with a modified form of post bars;

Figure 11 is a perspective view of another embodiment of the invention; and

Figure 12 is a cross sectional view of the embodiment illustrated in Figure 11.

In the drawings, the reference numeral 2 indicates a pair of cover members connected to opposite edges of a pair of compression members 3 and 4 having upstanding side walls 5 and 6, respectively. A metal plate member 7 is secured to each compression member by means of rivets 8 or similar securing means. The inner edge of each cover member is positioned between the upstanding side wall of one compression member and one plate member 7 and is permanently held therein by means of the rivets 8 which pass therethrough. The plate member 7 is provided with a horizontal flange 9, overlying the outer edge of the compression member, and a vertical flange 10 at each end of the plate member.

The flanges 9 and 10 facilitate proper positioning of a pair of post bars 11 and maintain the post bars in position in the binder. The post bars are of a length equal to the distance between the flanges 10 and are each provided with a projection 12 on each end so that longitudinal displacement of the post bars is impossible after they have been properly positioned. Each post bar is provided at its top edge with a plurality of projections 13 which are preferably formed by bending the edge of the post bar. The lower edges of the post bars may have similar projections to increase the effective thickness of the post bars. The lower edge is also provided with a plurality of notches 14 to provide adequate clearance for various parts of the binder mechanism.

A plurality of sheet retaining posts or prongs 15 are permanently secured to each post bar 11 in any suitable manner. The sheet retaining posts or prongs are shown as being curved in cross section so as to provide a greater area of contact with the edges of the apertures 16 of the sheets 17 impaled thereon. It is obvious, however that flat prongs or prongs of any desired configuration can be substituted for the prongs shown in the drawings. Each post bar 11 is provided at its upper edge with a notch 18 opposite each sheet retaining prong secured to the other post bar so that the free end of each prong may be positioned under the flange 9 of the opposite post bar when the binder is compressed to its minimum position.

A modified form of post bar 19 having round telescoping sheet retaining posts or prongs 20 and 21 is shown in Figure 10. In this embodiment the bars project slightly above the flanges 9. A plurality of projections 22 are provided to fit under the flanges 9. The lower edge of each post bar may be provided with a plurality of projections 23 which increase the effective thickness of the bar.

In Figures 11 and 12 one of the post bars and one edge of the binder are the same as in the other modifications. The other edge of the binder is provided with a hinged plate 24 to which a post bar 25 is permanently secured by riveting or welding.

The binder is provided with a back member which includes a flat plate 26 and a rounded plate 27 secured at one end by means of a tongue 28 which projects through a slot 29 in the plate 26 and is clinched thereagainst. The plate member 26 is provided with a depression 30 adjacent the slot 29 so that the bent over ends of the tongue 28

28 do not project above the surface of the plate. A reinforcing bridge member 31 may be positioned to straddle the tongue 28 to furnish added rigidity to the connection between the members 5 26 and 27. The rounded plate 27 is provided with a metal strap 32 welded thereto to support it at its opposite end. The plate member 26 is provided with a plurality of longitudinal slots 33 for a purpose to be hereinafter described.

10 The compression members 3 and 4 are cut out on their inner edges, as indicated at 34, to allow room for a centralizing bar 35 positioned adjacent the plate member 26 by means of rivets or studs 36 which are permanently fixed to the bar 15 35 and project through the slots 33. The centralizing bar is connected to the compression members 3 and 4 by means of a plurality of toggle links 37. Accordingly, whenever the compression members 3 and 4 move transversely, the centralizing bar must move longitudinally. If the longitudinal movement of the bar is stopped at any point, further transverse movement of the compression members in the same direction is prevented until the stop means is released. The 20 slots 33 are of uniform length and provide positive stops to limit the total travel of the bar 35 and consequently of the compression members. Opposite ends of the plate member 26 are bent up, as indicated at 38, to provide a pair of channel members in which the ends of the compression members are adapted to move transversely.

A plate member 39 is secured against the underside of the back plate 26 by means of the rivets or studs 36 which secure the bar 35 against the top side of the back plate. One edge of the plate 39 is provided with a plurality of teeth or similar projections 40. Since the plate or rack 39 is rigidly connected to the centralizing bar 35 by the studs 36, any control of the motion of the member 39 will similarly control the motion of the bar 35 and the compression members 3 and 4.

A stud 41 secures a pair of superimposed pawl members 42 to the back plate 26 in proximity to the rack 39 so that the pawl teeth may engage the teeth 40 of the rack. The rack is as thick as the combined thickness of the two pawl members so that the teeth of either pawl member may have a substantial engagement with the teeth of the rack. The teeth of the pawl members 42 are offset longitudinally relative to each other so that when the pawls are in engagement with the teeth 40 and the binder is compressed each pawl member engages the teeth 40 alternately to provide positive stops against outward movement at a plurality of closely spaced points. In order to provide a positive stop it is necessary for the teeth to have substantial dimensions. The substantial size of the teeth necessary for strength makes it impossible to secure fine adjustment 50 with a single pawl member. With two offset pawl members however, it is possible to adjust the compression members to fit very closely against the contents of the binder.

A flat spring 43 having one end secured to the plate 26 at 44 and the other end secured to the upper end of the pawl at 45 is provided for each of the pawls 42. The springs 43 constantly urge the pawl members into engagement with the teeth 40 to prevent outward transverse movement of the compression members.

Disengagement of the pawl members 42 from the teeth 40 against the action of the springs 43 is accomplished by means of a lever 46 which is pivoted to the back plate 26 at 47 and has a pin 75 48 positioned in a notch 49 in the lower end of

each pawl member. The lower end of the lever 46 is bent around the end of the back plate 26, as indicated at 50, and is provided with a handle 51 accessible from the end of the binder so that the lever may be shifted easily. A plate member 5 52 bent around the end of the back plate 26 is provided with a notch 53 in which the end of the lever is positioned. The notch 53 is just wide enough to regulate the lateral movement of the lever. The plate 52 is spaced from the back 10 plate by means of a pair of metal blocks 54 to allow a space for the ends 55 of the metal strap 32 to be received between the back plate 26 and the plate 52. The plate 52, spacing blocks 54 and back plate 26 are welded together to form a 15 rigid structure.

The lever 46 is provided with an aperture 56 adapted to fit over a projection 57 depending from the back plate 26 to hold the lever in open position and to prevent accidental movement of 20 the lever. The projection 57 is rounded somewhat so that lateral pressure on the lever 46 will disengage the aperture 56 and the projection 57. It will be understood that the purpose of the aperture 56 and the projection 57 is not to prevent movement of the lever 46, but is merely to prevent accidental movement. The lever is provided with a shoulder 58 against which a permanent lock is adapted to abut. No permanent lock is illustrated, but a suitable 30 permanent lock is disclosed in the prior application of Paul O. Unger, Serial No. 708,757, filed January 29, 1934, which issued as Patent No. 1,996,940 on April 9, 1935.

The binder is provided with a cover plate 59 35 having depending flanges 60 to space it above the toggle mechanism of the binder. The flanges 60 are notched, as indicated at 61, to provide the necessary clearance for the toggle links. The cover plate imparts a finished appearance to the 40 inside of the binder back and protects the mechanism.

The operation of the binder is very simple. Starting with the binder in closed position as shown in Figure 1, the lever 46 is moved to the right to move the pawls 42 out of engagement with the rack 39. Figure 2 clearly shows the structure causing the pawls to move out of engagement with the rack. The compression members may then be moved outwardly by pulling on 45 the cover members or compression members until the binder is open wide enough to permit removal of bars 11 and prongs 15 to receive the sheets. The sheets are then impaled on the posts or prongs of the post bars and the sheet retaining unit is positioned between the compression members. The lever is then preferably moved to closed position and the compression members are moved inwardly until they fit tightly against the post bars. During this inward movement of the 50 compression members one pawl is moved into engagement with the teeth 40 by its spring 43 while the other one is forced up the incline of the teeth 49 out of engagement. When the second pawl falls into engagement with the next 55 tooth 40, the first pawl is moved up the incline. If desired, the lever can be left in open position until the compression members are moved in as far as possible, and then moved to closed position. In either case the compression members are adjusted very closely to the contents of the 60 binder.

In Figures 8 and 9 a modified form of securing means is shown for holding the rounded plate 75 27 to the flat plate 62 which replaces the plate

26. The plate 62 is provided with a plurality of slots 63 and depressed portions 64 adjacent thereto. A reinforcing plate 65 welded to the rounded plate 27 is provided with a plurality of tongues 66 adapted to project through the slots 63 and be bent against the depressed portions of the plate 62 to secure the rounded back plate to the flat plate.

10 The only other difference between the embodiment illustrated in Figures 8 and 9 and the embodiment of Figures 1 to 7, inclusive, is in the specific means for moving the lever 67 which replaces the lever 46. The lever 67 is provided with a lateral extension 68 which is provided with a plurality of spaced apertures 69. A cylinder lock 70 is secured to the plate 62 adjacent the end of the lever 67 by means of a housing 71. The shaft 72 of the lock projects beyond the housing and has a toothed wheel 73 rigidly fixed thereto. The teeth of the wheel 73 engage the apertures 69 so that when the shaft is rotated by means of a key 74 the teeth of the wheel 73 move the lever so that the pawls are moved into and out of engagement with the rack. The lock 70 is constructed so that the key 74 may be moved therefrom only when the pawls are in engagement with the rack. This arrangement prevents any one from leaving the book in open condition without leaving visible evidence of the fact.

30 The end of the shaft 72 is supported by means of a tongue 75 struck out of the plate 62. The shaft is provided with a stop member 76 which abuts or engages the left-hand side of a lug 77, as seen in Figure 9, to prevent movement of the shaft and lever beyond a predetermined point in one direction. The lug 77 is struck out from the lever 67. Movement of the lever in the other direction is limited by the end 78 of the lever which abuts the side wall of the housing 71 when the pawls are fully disengaged from the teeth of the rack. The lever is provided with a shoulder 79 against which a permanent lock may be positioned.

40 When the lever is in locked position, a space is provided adjacent thereto for the reception of a permanent lock. The lever is protected against tampering because the stop member 76 which abuts against the lug 77 prevents any movement of the lever from its locked position. The only way possible to move the stop member 76 is by rotation of the shaft 72, and this can be accomplished only by use of the proper key.

50 Although we have described our invention in considerable detail, it will be understood that the description thereof is illustrative rather than restrictive, as many details may be modified or changed without departing from the spirit or scope of the invention. Accordingly, we do not desire to be restricted to the exact details of construction described, except as limited by the appended claims.

55 We claim:

1. In a loose-leaf binder, a back plate provided with a plurality of slots, a pair of transversely movable compression members, a bar adapted to control the transverse movement of said compression members, a second bar rigidly secured to said first mentioned bar by means of a plurality of studs, said studs passing through said slots to limit the movement of said bars, projections on said second mentioned bar, and a pair of relatively offset pawl members engageable with said projections to prevent movement of said bars in one direction.

70 2. In a loose-leaf binder, a back plate, a lon-

5 gitudinally movable bar positioned adjacent one surface of said back plate, a pair of transversely movable compression members, the movement of said compression members being controlled by the longitudinal movement of said bar, a second bar rigidly secured to said first mentioned bar, said second bar being positioned adjacent the opposite surface of said back plate, a plurality of teeth on said second mentioned bar, and a pair of superimposed pawl members engageable with said teeth to control the movement of said bars in one direction, said pawls being relatively offset to increase the fineness of adjustment of said compression members.

10 3. In a loose-leaf binder, a back member, a pair of compression members movable transversely relative to said back member, a bar connected to said compression members and movable longitudinally of said back member when said compression members are moved transversely, a rack rigidly connected to said bar, a pair of relatively offset pawl members engageable with said rack to prevent longitudinal movement of said bar in one direction, and a single lever operable to move both of said pawl members into and out of engagement with said rack.

15 4. In a loose-leaf binder, a pair of transversely movable compression members, means to control the outward movement of said compression members, said means including a bar provided with a plurality of teeth on one edge and a pair of superimposed pawl members adapted to engage said teeth alternately during the inward movement of said compression members to provide positive stops against outward movement at a plurality of closely spaced points, and a single lever operable to move said superimposed pawl members out of engagement with said teeth to permit outward movement of said compression members.

20 5. In a loose-leaf binder, a back member, a pair of compression members movable transversely of each other, a rack positioned adjacent said back member and operatively connected to said compression members, a pair of pawls superimposed in planes parallel to said back member, said pawls being pivoted on said back member and engageable with said rack at intervals less than the distance between adjacent teeth of said rack to prevent outward movement of said compression members, and key operated means for moving said pawls into and out of locking position.

25 6. In a loose-leaf binder, a pair of compression members, a rack connected to said compression members, a stationary back plate, a pair of superimposed pawls pivoted to said back plate, spring means tending to move said pawls into engagement with said rack to prevent outward movement of said compression members, a lever pivoted to said back plate, said lever engaging said pawl members, and key operated means engaging said lever for moving said pawls out of engagement with said rack against the action of said spring.

30 7. In a loose-leaf binder, a pair of compression members, a rack connected to said compression members, a back member, a pair of superimposed pawl members connected to said back member, a lever pivoted to said back member, said lever engaging said pawl members, and a single key operated means engaging said lever for moving said pawl members into and out of engagement with said rack.

35 8. In a loose-leaf binder, a pair of compres-

- 5 said side walls, a pair of cover members, each of
5 said cover members having one edge secured be-
tween one of said side walls and its adjacent
plate member, one of said plate members having
a flange overhanging the top of the side wall of
one of said compression members, a post bar
hingedly fixed to said other compression member,
and a detachable post bar having sheet retain-
ing prongs adapted to cooperate with said fixed
post bar to retain a plurality of sheets in orderly
arrangement, the top edge of said detachable
post bar engaging with said flange to prevent
accidental displacement of the sheets. 5
- 10 6. In a loose-leaf binder, a pair of cover mem-
bers, a pair of plate members secured to the
inner edges of said cover members, said cover
members being adapted to move said plate mem-
bers transversely of each other, a post bar hinged-
ly fixed to one of said plate members, an unat-
tached post bar adapted to cooperate with said
hingedly fixed post bar to retain a plurality of
sheets in orderly arrangement, a plurality of pro-
jections on said unattached post bar, and means
on said other plate member engaging the projec-
tions on said unattached post bar for positively
retaining said unattached post bar against longi-
tudinal movement relative to said last mentioned
plate member. 15
- 15 7. In a loose-leaf binder, a back member, a
longitudinally movable bar positioned adjacent
said back member, a pair of flanged compression
members connected to said bar and movable
transversely by the longitudinal movement of said
bar, a rack rigidly secured to said bar, a pawl
member engageable with said rack to control
movement of said bar in one direction, and a pair
of detachable post bars provided with posts upon
which a plurality of sheets may be impaled, said
post bars being adapted to retain one edge of a
plurality of sheets between said compression
members, and a plurality of projections on said
post bars, said projections being adapted to en-
gage the flanges of said compression members
to prevent accidental displacement of the sheets. 20
- 20 8. In a loose-leaf binder, a back member, a
longitudinally movable bar positioned adjacent
said back member, a pair of flanged compression
members connected to said bar and movable
transversely by the longitudinal movement of said
bar, a pair of detachable post bars provided with
posts upon which a plurality of sheets may be im-
paled, said post bars being adapted to retain
one edge of a plurality of sheets between said
compression members, and a plurality of projec-
tions on said post bars, said projections being
adapted to engage the flanges of said compression
members to prevent accidental displacement of
the sheets. 25
- 25 9. In a loose-leaf binder, a pair of compres-
sion members, a rack connected to said compres-
sion members, a back member, a pair of super-
imposed pawl members pivoted to said back mem-
ber, a lever pivoted to said back member and
having a pin in engagement with said pawl mem-
bers, and a key operated shaft, said lever being
operable by means of said key operated shaft. 30
- 30 10. In a loose-leaf binder, a pair of compres-
sion members, a rack connected to said compres-
sion members, a back member, a pair of pawl
members pivoted to said back member, and a
lever pivoted to said back member and engageable
with said pawl members to move said pawl mem-
bers into and out of engagement with said rack. 35
- 35 11. In a loose-leaf binder, a pair of transversely
movable compression members, each of said com-
pression members having an upstanding side wall
along its outer edge, a plate member adjacent
each of said side walls, a pair of cover members,
each of said cover members having an edge per-
manently secured between one of said side walls
and its adjacent plate member to form two up-
standing units extending along the outer edges
of said compression members, a post bar hingedly
fixed to one of said units, an unattached post bar
adapted to cooperate with said hingedly fixed
post bar to retain a plurality of sheets in orderly
arrangement, and means on said other unit for
positively retaining said unattached post bar in
engagement with said last mentioned unit. 40
- 40 12. In a loose-leaf binder, a pair of compres-
sion members, a rack operatively connected to
said compression members, a back plate, a pair of
pawls adapted to engage said rack, said pawls
being superimposed in planes parallel to said
back plate, a lever pivoted on said back plate and
engaging said pawls, and means to move said
lever on said back plate to move said pawls into
and out of engagement with said rack. 45
- 45 13. In a loose-leaf binder, a flat back plate,
a pair of compression members movable trans-
versely relative to said back plate, a rack posi-
tioned against said back plate and operatively
connected to said compression members, and a
pair of superimposed pawls offset relatively to
each other and movable in planes parallel to the
plane of said rack and said back plate, said pawl
members being engageable with said rack to con-
trol the outward movement of said compression
members. 50
- 50 14. In a loose-leaf binder, a back member, a
pair of compression members movable transverse-
ly relative to said back member, a flat plate
member positioned against said back member, a
plurality of projections on one edge of said plate
member, and a pair of superimposed pawl mem-
bers offset relatively to each other, said plate
member being operatively connected to said com-
pression members independently of said pawl
members, said pawl members being engageable
70 with said projections to control the outward
movement of said compression members. 55
- 75 15. In a loose-leaf binder, a pair of compres-
sion members, each of said compression members
having an upstanding side wall at its outer lon-
gitudinal edge, a plate member adjacent each of
- 75 16. In a loose-leaf binder, a pair of cover mem-
bers, a pair of plate members secured to the
inner edges of said cover members, said cover
members being adapted to move said plate mem-
bers transversely of each other, a post bar hinged-
ly fixed to one of said plate members, an unat-
tached post bar adapted to cooperate with said
hingedly fixed post bar to retain a plurality of
sheets in orderly arrangement, a plurality of pro-
jections on said unattached post bar, and means
on said other plate member engaging the projec-
tions on said unattached post bar for positively
retaining said unattached post bar against longi-
tudinal movement relative to said last mentioned
plate member. 20
- 80 17. In a loose-leaf binder, a back member, a
longitudinally movable bar positioned adjacent
said back member, a pair of flanged compression
members connected to said bar and movable
transversely by the longitudinal movement of said
bar, a rack rigidly secured to said bar, a pawl
member engageable with said rack to control
movement of said bar in one direction, and a pair
of detachable post bars provided with posts upon
which a plurality of sheets may be impaled, said
post bars being adapted to retain one edge of a
plurality of sheets between said compression
members, and a plurality of projections on said
post bars, said projections being adapted to en-
gage the flanges of said compression members
to prevent accidental displacement of the sheets. 25
- 85 18. In a loose-leaf binder, a back member, a
longitudinally movable bar positioned adjacent
said back member, a pair of flanged compression
members connected to said bar and movable
transversely by the longitudinal movement of said
bar, a pair of detachable post bars provided with
posts upon which a plurality of sheets may be im-
paled, said post bars being adapted to retain
one edge of a plurality of sheets between said
compression members, and a plurality of projec-
tions on said post bars, said projections being
adapted to engage the flanges of said compression
members to prevent accidental displacement of
the sheets. 30
- 90 19. In a loose-leaf binder, a back plate, a rack
slidably secured to said back plate, a pair of
relatively offset superimposed pawls secured to
said back plate and pivoted to move in planes
parallel to said back plate, and a pair of spring
members mounted on said back plate, said spring
members normally urging said pawls into engage-
ment with said rack. 35
- 95 20. In a loose-leaf binder, a back plate, a rack
secured to said back plate and movable longitu-
dinally thereof in a plane parallel thereto, a pair
of relatively offset pawls pivoted to move in
planes parallel to said back plate, and a pair of
spring members secured to said back plate, said
spring members normally urging said pawls into
engagement with said rack. 40

21. In a loose-leaf binder, a back plate, a rack secured to said back plate and movable longitudinally thereof in a plane parallel thereto, a pair of relatively offset pawls pivoted to move in planes parallel to the plane of said back plate, spring means urging said pawls into engagement with
- 5 said rack, and a lever operable to move both of said pawls out of engagement with said rack against the action of said spring means.
